UNITED STATES PATENT OFFICE.

JAMES S. CROSSLEY, OF SOLVAY, NEW YORK.

ELECTRIC SWITCH.

1,213,751.

Specification of Letters Patent. Patented Jan. 23, 1917.

Application filed October 29, 1914. Serial No. 869,285.

To all whom it may concern:

Be it known that I, JAMES S. CROSSLEY, a citizen of the United States, and resident of Solvay, county of Onondaga, State of New York, have invented certain new and useful Improvements in Electric Switches, of which the following is a specification.

My invention relates to electric switches and more particularly to a switch mechanism suitable for use in connection with electric lamp sockets and the like.

It is my object to generally improve switches of this character and to provide a quick make and break switch having a wide double break which is securely held in place so that it will not work loose from the base which supports it.

The above and other objects and the novel features of my invention will be apparent from the following description taken in connection with the drawing in which,

Figure 1 is a central vertical sectional view of a switch embodying my invention locked in place on an electric lamp socket, the outer inclosing shell of the latter being omitted; Fig. 2 is a plan view of the switch mechanism and the base on which it is supported; Fig. 3 is an enlarged side elevation of the switch removed from the base; Fig. 4 is a perspective view of the parts of the switch mechanism shown disassembled.

Referring to the drawing and particularly Figs. 1 and 2, the lamp socket comprises the usual insulating buttons or bases A and B which are recessed as at 10 and 11 in their abutting faces to form a cavity within which the switch works. The lower base B has the usual screw shell 12 secured to its outer side, the screw shell 12 being electrically connected to a line terminal, not shown, which is secured to the upper button A and fits in the recess 13 of the lower button B. Another line terminal 14 secured in a recess 15 in the bottom button B is connected by means of a plate 16 with a vertical switch contact 17 located on the opposite side of the recess 11 from the switch contact 18. Both the switch contacts 17 and 18 are curved outwardly at their upper ends as shown and the switch contact 18 is connected by a bent plate 19 with the center lamp contact 20. In the present case the strip of material constituting the center lamp contact and the plate 19 and spring contact 18 are made integral and fastened to the base B by means of a rivet

21 which extends centrally through the base.

The bases A and B and the shell 12 are fastened together by suitable screws not shown which extend through the holes 22 as is usual.

The switch contacts 17 and 18 are spaced apart a suitable distance in the recess 11 and a switch member 23 is operated by a key 24 to open and close the circuit between said contacts.

The switch member 23 consists of a single strip of conducting material bent U-shaped or into a stirrup and having a transversely extending part 25 which connects and is formed integral with the two substantially parallel parts 26 and 27. The arms 26 and 27 are each bent outwardly as at 28 and then again parallel to the sections 26 and 27 as at 29. The portions 29 are pierced at their ends to provide holes 30 to receive lugs 31 formed integral and extending outwardly from a supporting frame F, whereby the switch member 23 is pivotally supported by the frame F at a point between the top and bottom of the frame.

The frame F is made of a single plate of metal and has a bottom portion 32 which is integrally joined to two parallel side members 33 and 34, the side member 34 being broken away in Fig. 4 to more clearly show the end members 35 and 36 which are also integrally connected to the bottom 32. The sides and ends are arranged at right angles to the bottom 32 and the frame is secured to the base B by a screw 37 engaging a hole 38 in the bottom 32.

The lateral sides 33 and 34 of the frame F are each cut away at their forward ends as at 39 to provide two forwardly extending points 40 and 41 at the top and bottom of the frame at each side thereof. The forwardly projecting points 40 and 41 are bent outwardly and are disposed in the path of the bends or shoulders 28 on the switch member 23 so as to provide stops for the switch member on each side of its swing or oscillation on the pivot lugs 31, as will be apparent from a later description of the operation.

The key 24 for operating the switch is disposed outside of the cavity formed by the recesses 10 and 11 and is securely fastened to a spindle 42 journaled in recesses 43 and 44 in the end parts 35 and 36 of the frame F. Two elliptical cams 45 and 46 are fixed on the spindle 42 in such a position that

their major axes are disposed at right angles to each other, the cams being spaced apart by a sleeve 47 on the spindle 42. The cams 45 and 46 and the intermediate sleeve 5 are disposed between the upright parts 35 and 36 and a lug 48 fixed on the spindle on the outer side of the upright part 36 holds the spindle and parts thereon in place on the frame though the spindle and parts thereon 10 may be lifted vertically out of the slots 43 and 44. The lug 48 also prevents end motion of the spindle in one direction and the hub 49 of the key prevents endwise motion in the opposite direction.

15 The device by means of which the rotation of the key is transmitted to the switch member to effect the operation of the latter consists of a plate 50, a pin 51 and a spiral spring 52. The plate 50 has a transverse 20 bend 53 intermediate its ends, the lower side of which rests on the sleeve 47 and the upper side serves as a groove to receive the cross pin 54 which holds the plate 50 in place and forms a fulcrum or pivot therefor on which 25 the plate may oscillate. The spindle 42 may be rotated in either direction by the key 24 and the pivoted switch actuating plate 50 will therefore operate the switch when the key is turned in either direction.

30 The pin 54 performs an important function in addition to its function as a pivot or fulcrum for the oscillating plate 50 since it projects through the holes 55 in the opposite sides 33 and 34 of the frame F and laterally from said side members of the frame into notches 56 and 57 in the top face of the base B. The notches 56 and 57 open into the lateral faces of the recess in which the frame F is mounted and also opening 40 into the top face of the insulating member B as shown in Fig. 2. The notches 56 and 57 receive and closely fit around the ends of the cross pin 54 and thereby lock the upper end of the frame securely in place in its 45 recess so that it will not be permitted to swivel about the securing screw 37. The bottom face of the insulating member A abuts against the top face of the insulating member B and consequently closes the 50 notches 56 and 57 at the top but permits the frame F and the pin 54 thereon to be readily assembled in place in the recess in the bottom insulating member. In practice I have found that a single screw carrying 55 the frame or yoke for supporting the switch mechanism is not a sufficient fastening means as the operation of the mechanism tends to turn the yoke or frame about the screw and considerable damage may result 60 if the frame moves. Therefore I have supplemented the securing screw 37 with a steadyng device in the form of the pin 54 which also serves as a fulcrum for the oscillating plate 50.

65 At one end the pin 51 has a head 58 pro-

vided with an eye 59 and an entrance slot 60 which leads into the eye 59. The entrance slot 60 is narrower than the width of the eye 59 and is of sufficient width to receive the edge of a transverse lug 61 provided by 70 cutting openings 62 and 63 in one end of the oscillating plate 50, the said end of the plate being bent as at 64 at right angles to the body of the plate having the transverse bend 53 therein. The transverse part 61 in the 75 right angle bend 64, however, is wider than the entrance slot 60 of the head 58 so that the plate 50 and the pin 51 will not come apart by a pull when they are in line or even at a slight angle to each other, it being only 80 possible to assemble and disassemble them by passing the cross part 61 edgewise into the entrance slot 60, the parts then being at right angles to each other and the opening 85 62 being of sufficient size to permit the necessary angular movement between the two pieces 50 and 51. The end of the pin 51 projects through a hole 65 in the transverse part 25 of the switch member 23 when the parts are assembled and the spiral spring 52 fits 90 around the pin 51, one end thereof pressing against the shoulder 66 of the head 58 and the other end pressing against the inner side of the transverse part 25 of the switch member.

95 The plate 50 being pivoted above or to one side of the operating spindle 42 and the switch member 23 being pivoted on an axis below the pivot of the plate 50, when the plate 50 is rocked on its pivot the switch member 23 will be thrown from one side to the opposite side about its pivot with a snap action by the oscillation of the head of the pin due to the oscillation of the plate 50. Changing the position of the head 58 of the 100 pin from one side to the opposite side of the pivotal connection between the switch member 23 and the frame causes the spring 52 to be tensioned while crossing the pivotal point 105 of the switch member 23 and released when the head 58 reaches the opposite side of the pivot of the switch member 23.

110 The plate 50 is operated by the cams 45 and 46 engaging the under side of the plate 50 on opposite sides of the pivot pin 54. The 115 cams being substantially in the form of ellipses and placed with their axes at right angles to each other will rock the switch member 23 from open to closed position or vice versa every quarter turn of the key 24. As shown in the figures the right hand end of the plate 50 will be raised by the high 120 points of the cam 45 and the switch will be open whenever the key is moved into such a position that the cam 45 engages the under side of the plate 50. On the other hand when the cam 46 engages the underside of the plate the left hand end of the plate 50 will be raised and the switch plate 23 will be 125 thrown to closed position, as shown in Fig. 3. 130

The operation of the switch will be apparent from the foregoing description and while I have shown and described the construction in detail I do not wish to be limited to the exact devices employed as numerous changes within the scope of the claims may be made without departing from the spirit of the invention.

Having described my invention what I claim and desire to secure by Letters-Patent is,

1. In an electric switch, the combination of two insulating members secured together face to face and having registering cavities in their abutting faces to provide a switch chamber, switch mechanism in said chamber comprising a frame having sides, ends and a bottom, a fastening device engaging the bottom of said frame and the insulating member in which the frame is fitted to secure the frame in the cavity therein, a rotatable operating member mounted in the ends of said frame, a switch member, a pivoted switch actuating device operable by turning said spindle in either direction, and a pin upon which said device is pivoted, said pin being disposed at right angles to the spindle and mounted in the sides of said frame, the opposite ends of said pin projecting beyond the outer sides of said frame, the insulating member to which said frame is secured having oppositely disposed similar recesses opening into the cavity therein and also opening into the top face thereof and adapted to receive and closely fit around the projecting ends of said pin and prevent the frame swiveling on said screw when the spindle is turned in either direction to operate the switch.
2. In an electric switch, the combination of two insulating members secured together face to face and having registering cavities in their abutting faces to provide a switch chamber, switch mechanism in said chamber comprising a frame fitted in the cavity in one of said members and having sides, ends and a bottom, a screw engaging the bottom of said frame and the insulating member in which the frame is fitted to secure the frame therein, a spindle mounted in the ends of said frame and rotatable in either direction, a switch member, a pivoted switch actuating device operable by turning said spindle in either direction, and a pin upon which said device is pivoted, said pin being disposed at right angles to the spindle and mounted in the sides of said frame, the opposite ends of said pin projecting beyond the outer sides of said frame, the insulating member to which said frame is secured having oppositely disposed similar recesses opening into the cavity therein and also opening into the top face thereof and adapted to receive and closely fit around the projecting ends of said pin and prevent the frame swiveling on said screw when the spindle is turned in either direction to operate the switch.

In testimony whereof I affix my signature in presence of two witnesses.

JAMES S. CROSSLEY.
